FRANK TATÁR, OF NEW YORK, N. Y.

MEASURING-RECEPTACLE.

1,097,570.

Specification of Letters Patent.

Patented May 19, 1914.

Application filed August 5, 1913. Serial No. 783,134.

To all whom it may concern:

Be it known that I, FRANK TATÁR, a subject of the King of Hungary, and resident of the city of New York, in the county of 5 New York and State of New York, have invented certain new and useful Improvements in Measuring-Receptacles, of which the following is a specification.

The present invention relates to liquid 10 measuring receptacles especially adapted for use of grocers.

Grocers, in selling liquid substances, such as for instance milk, kerosene, etc., use receptacles of predetermined sizes which are 15 dipped into the liquid substance and then tilted in order to pour the liquid from the measuring receptacle into the vessel of the purchaser. In tilting the measuring receptacle inasmuch as the same is full to its 20 brim part of the liquid substance is often spilled on the counter or floor resulting thereby in a loss to the purchaser and in a sciling of the counter or floor.

One of the objects of the present invention is to obviate these defects and to provide a simple and inexpensive measuring receptacle which need not be tilted in order to discharge its contents.

With these and other objects in view, 30 which will more fully appear as the nature of the invention is better understood, the same consists in the combination, arrangement and construction of parts hereinafter fully described, pointed out in the appended 35 claim and illustrated in the accompanying drawings, it being understood that many changes may be made in the size and proportion of the several parts and details of construction within the scope of the appended 40 claim without departing from the spirit or sacrificing any of the advantages of the invention.

One of the many possible embodiments of the invention is illustrated in the accompanying drawings, in which:—

Figure 1 is a central vertical section taken through a measuring receptacle constructed in accordance with the present invention, partly in elevation; and Fig. 2 is a 50 front elevation of said receptacle.

In the drawings, the numeral 10 indicates a receptacle, preferably cylindrical in shape, and adapted to hold a predetermined quantity of liquid substance. To this receptacle 55 is attached a handle 11, extending a substan-

tial distance above the mouth of the receptacle and being provided at its upper end with a bend 12 at which it can be grasped with the hand. In the bottom 13 of the receptacle is formed a discharge opening 14, 60 around the same being disposed a valve seat 15 for a valve 16, the latter being, preferably, conical and attached to a spring 17, which is secured in any suitable manner at 18 to the wall of the receptacle. The tendency of this spring is to hold the valve on its seat.

For unseating the valve, a mechanism is provided, comprising a rod 19, which is disposed substantially parallel to the handle 70 11, its upper bent end 20 being arranged in proximity to the bend 12 of the handle 11. This rod is pivoted at 21 to a lever 22, the latter being fulcrumed at 23 to lugs 24, which are carried by the handle 11. To the 75 other end of the lever 22 is pivotally attached at 25 a rod 26, the lower end of which is fork-shaped, as shown at 27. This fork-shaped end is in engagement with the spring 17, its prongs preventing a disengagement of said rod from the spring. The rod 19 is shiftably arranged in a guide 80 28, that is fastened to the handle 11, and in a similar manner is arranged the rod 26 in a guide 29, the latter being secured in any 85 suitable manner to the wall of the vessel 10.

The valve 16 is guided in its movement by a downwardly projecting extension 30 of the valve seat, which tends to keep the longitudinal axis of said valve in alinement 90 with the center of the discharge opening 14 while the said valve is being unseated.

The operation of this device is as follows: The parts are normally in the positions shown in the drawings, that is to say the 95 spring 17 keeps the valve on its seat. In use, the vessel is dipped into the liquid substance kept in the container. When properly filled with liquid, the receptacle is withdrawn and transferred in an upright position in alinement with the mouth of the purchaser's vessel. The rod 19 is then pulled upward by engaging its bent end 20 and forcing it toward the bend 12 of the handle 11. By this operation, the rod 26 105 is shifted downward, whereby it causes a downward movement of the spring 17, and thereby an unseating of the valve 16. The liquid flows then through the discharge opening into the vessel. In order to bring 110

the parts into their normal positions, the rod 19 is released, the spring 17 forcing then the valve back into its closing position.

What I claim is:—

- 5 In a measuring device, the combination with a receptacle having a discharge opening in its bottom, of a handle attached to said receptacle, a valve outside of said receptacle adapted to close said opening, a
10 spring disposed outside of said receptacle carrying said valve and forcing it into closing position, and a plurality of link connected rods shiftably arranged relative to

said handle outside of said receptacle, one of said rods engaging said spring and the 15 upper end of another one of said rods being arranged in close proximity to the upper end of said handle.

Signed at New York, in the county of New York and State of New York, this 6th 20 day of May, A. D. 1913.

FRANK TATÁR.
